UNITED STATES PATENT OFFICE.

FRANKLIN PETER GILBERT, OF PALMERTON, PENNSYLVANIA, ASSIGNOR OF ONE-HALF TO JACOB A. MOONEY, OF PALMERTON, PENNSYLVANIA.

COMPOSITION ROAD-BED.

1,099,697.

Specification of Letters Patent.

Patented June 9, 1914.

Application filed November 6, 1912. Serial No. 729,840.

To all whom it may concern:

Be it known that I, FRANKLIN P. GILBERT, a citizen of the United States, residing at Palmerton, in the county of Carbon and State of Pennsylvania, have invented certain new and useful Improvements in Composition Road-Beds, of which the following is a specification.

This invention relates to certain new and useful improvements in reinforced concrete roadbeds for railways and it has for its objects among others to provide a simplified and cheapened construction of reinforced concrete bed provided with cavities or depressions to receive the rail-supporting devices and also a centrally disposed trough for the reception of water.

It has for a further object to provide a concrete base upon which the rail chairs or fastening devices are supported.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which—

Figure 1 is a perspective view of the invention with parts in section and portions broken away showing an improved road bed and rails mounted thereon. Fig. 2 is a vertical transverse section through Fig. 1. Fig. 3 is a perspective view of one of the chair supporting bases. Fig. 4 is a perspective view of one of the base-supporting springs.

Like numerals of reference indicate like parts throughout the several views.

In carrying out my invention, I form a base 1 of cement or analogous material suitably reinforced by metal reinforcing members 2, as seen in Figs. 1 and 2. The roadbed 1 is formed with cavities or chambers or depressions 3, above which the rails are designed to be supported, and with an intermediate portion 4 for the reception of water for the usual purpose.

5 are the rails. These are supported upon the rail-supporting bases 6 which are formed of cement or analogous material having the roughened or serrated portions 7 near each end upon the upper face, the intermediate portion being preferably left smooth, as shown at 8. Through each of the

serrated portions is formed a vertical opening 9 for the reception of the bolts, as seen in Fig. 3. This rail-supporting base has the central body portion 10 which is designed to fit quite snugly within the recess or chamber 3 in the roadbed, as seen in Fig. 2, leaving the surrounding horizontal flange 11, as seen in Figs. 1, 2 and 3, which overlaps the upper face of the roadbed, as seen in Figs. 1 and 2.

12 is a spring of preferably the form shown in Fig. 4. It has its ends curled upwardly, as seen at 13, and its top portion is provided with openings 14 for the passage of the bolts.

In practice, the springs are placed within the chambers or cavities 3 in the roadbed, as seen in Figs. 1 and 2, the bolts 15 having been first disposed with their heads 16 embedded in the cement or similar material of which the base is formed, as seen clearly in Fig. 2, the openings 14 in the upper portion of the spring being slipped over the bolts. The rail-supporting base 6 is then placed in position, the bolts passing through the openings 9 thereof and the body portion of the rail-supporting base rests upon the spring. The rail-fastening devices 17 are then applied over the bolts and the nuts 18 applied after properly adjusting the fastening devices. As will be seen in Fig. 2, the fastening devices 17 are provided with elongated slots 19 so as to permit of proper adjustment of the rail-fastening devices. The rail-fastening devices are serrated or roughened on their under surfaces, as shown at 20, for coöperation with the roughened or serrated surfaces 7 of the rail-supporting base 6.

The springs 12 are of such tension as to normally hold the rail-supporting bases with their flanges 11 somewhat above the upper face of the roadbed, as seen in Fig. 2, so as to permit of the necessary elasticity and yielding when the weight of the train is upon the rails, the springs returning the supporting-bases to their normal positions after the train has passed. The under face of the flange 11 coming in contact with the upper face of the roadbed serves to limit the downward movement of the rail-supporting base and the ends of the spring will contact with the adjacent walls of the chamber 3 to limit the downward movement of the spring.

Modifications in detail may be resorted to

without departing from the spirit of the invention or sacrificing any of its advantages.

What is claimed as new is:—

- 5 1. A composition roadbed reinforced and having a pocket, a composition rail-supporting base vertically movable in said pocket, and rail-fastening devices supported on said base.
- 10 2. A composition roadbed reinforced and having a pocket, a composition rail-supporting base vertically movable in said pocket, and rail-fastening devices supported on said base, the adjacent faces of the base and rail-fastening devices being serrated.
- 15 3. A composition roadbed having a pocket, a composition rail-supporting base vertically movable in said pocket, resilient means in said pocket below said base, and rail-fastening devices supported on said base.
- 20 4. A roadbed having chambers therein,

25 rail-supporting bases mounted in the upper ends of said chambers, bowed resilient members resting on the bottoms of said chambers for yieldingly supporting said bases, said members having openings therein and their ends adapted to slide on the bottoms of the chambers under the weight of passing trains, rail-fastening devices supported on said bases, and bolts secured to the bottoms of 30 the chambers and extending up through the openings in the resilient members and through the bases and rail-fastening devices for fastening said devices to said bases and for retaining the resilient members in proper 35 position.

In testimony whereof I affix my signature in presence of two witnesses:

FRANKLIN PETER GILBERT.
